UNITED STATES PATENT OFFICE.

JAMES B. BILES, OF ELMA, WASHINGTON.

CHOPPING-BOARD.

SPECIFICATION forming part of Letters Patent No. 595,757, dated December 21, 1897.

Application filed May 3, 1897. Serial No. 634,928. (No model.)

To all whom it may concern:

Be it known that I, JAMES B. BILES, a citizen of the United States, residing at Elma, in the county of Chehalis and State of Washington, have invented certain new and useful Improvements in Chopping-Boards; and I do hereby declare the following to be a full, clear, and exact description of the invention, such as will enable others skilled in the art to which 5 it appertains to make and use the same.

This invention relates to certain new and useful improvements in devices designed for the support of a person or persons while cutting down a tree.

15 It has for its objects, among others, to provide a simple and cheap device for this purpose that shall be readily applied, possessing sufficient strength, having provision for the adjustment of the supporting board or plank, 20 and avoiding the necessity of cutting a notch in the tree for the support of the end of the board or plank.

25 Other objects and advantages of the invention will hereinafter appear and the novel features thereof will be specifically defined by the appended claims.

30 The invention is clearly illustrated in the accompanying drawings, which, with the letters of reference marked thereon, form a part of this specification, and in which—

35 Figure 1 is a plan view showing the support in position on the tree. Fig. 2 is a vertical section in the direction of the length of the plank. Fig. 3 is a vertical section at right angles to Fig. 2.

Like letters of reference indicate like parts throughout the several views.

Referring now to the details of the drawings by letter, A designates a metallic bracket 40 or frame comprising the two substantially parallel side pieces *aa*, of any required length, having their ends which are designed to engage the tree sharpened or pointed, as seen at *b*. These side pieces are connected by the 45 cross-bars B and C, the former being upon the upper side of the side pieces, as shown, and the latter upon the under side, for a purpose which will soon be made apparent. The cross-bars may be connected with the side 50 pieces in any suitable manner, as by being

bent over and welded to the side pieces on the outer surfaces thereof, so as to make a strong, solid, and durable frame.

D are hooks pivotally secured to the side pieces of the frame near the outer ends thereof, and in which hooks are adapted to be engaged the chains E. These chains are provided with the hooks or dogs F, which are adapted to engage in the tree.

G is the board or plank upon which the operator stands while sawing the tree.

In applying the device first drive the dogs F into the tree, as shown, so that the chains will extend at an angle of about twenty or twenty-five degrees, more or less. Then place 65 the metallic bracket or frame in position, as shown, at right angles to the tree. Then engage the chains in the hooks D on the side pieces of the frame and place the board or plank in position by placing its inner end 70 over the outer cross-bar and under the inner cross-bar in the manner shown. This firmly supports the board or plank, and when the operator places his weight upon the plank the pointed ends of the side pieces of the frame 75 will be forced into the tree and the whole device will be securely and firmly held in position.

The board or plank can be readily adjusted to different positions, as indicated by dotted 80 lines in Fig. 1, the plank being of considerable less width than the space between the side pieces of the frame.

A device constructed as above described can be quickly placed in position and as 85 quickly removed and set up on another tree. It comprises but few parts, can be easily carried from place to place, and its advantages will be appreciated by those having occasion to use such devices.

90 What is claimed as new is—

1. In a device of the character described, a frame having side pieces with pointed ends, cross-bars connecting the side pieces upon different horizontal planes, and a plank removably supported by said cross-bars, substantially as specified.

2. In a device of the character described, a metallic frame having side pieces pointed at one end and cross-bars connecting the side 100

pieces upon different planes, hooks upon the side pieces, and chains provided with dogs adapted to engage in a tree, all substantially as shown and described.

5 3. The combination with the frame having side pieces with pointed ends and connecting cross-bars upon different planes, of the plank adjustably supported by the cross-bars, the hooks on the side pieces and the chains hav-

ing one end provided with dogs adapted to engage in a tree, substantially as specified.

In testimony whereof I have signed this specification in the presence of two subscribing witnesses.

JAMES B. BILES.
